United States Patent Office.

WILLIAM H. SALTMARSH, OF WALTHAM, MASSACHUSETTS.

Letters Patent No. 72,686, dated December 24, 1867.

IMPROVEMENT IN BELT-SHIPPER FOR MULES.

The Schedule referred to in these Letters Patent and making part of the same.

TO ALL WHOM IT MAY CONCERN:

Be it known that I, WILLIAM H. SALTMARSH, of Waltham, in the county of Middlesex, and State of Massachusetts, have invented certain new and useful Improvements in Adjustable Belt-Shippers for Mules; and I do hereby declare that the following is a full and exact description thereof, reference being had to the accompanying drawings, and to the letters of reference marked thereon.

The nature of my invention consists in a device by which the belt-shopper is operated by the mule-carriage instead of the cam-shaft, as heretofore, the parts being so arranged that the belt may be shipped before the mule arrives at either terminus of its way; that is, by an adjustment, the shipper may operate when the mule is at any desired distance—seven inches, for instance—from the end of its way; the object of this arrangement being to diminish the speed of the mule before the brake goes on, thereby avoiding the strain on the wheels, gears, and other parts of the machine. The jar which always follows the change of the belt on a high-speeded mule, with the old cam-shopper, is entirely overcome by my improvement.

To enable others skilled in the art to make and use my invention, I will proceed to describe its construction and use. In the drawings—

Figure 1 is an end elevation of a mule, showing the mule-carriage and the belt-shipping device, all other details being omitted.

Figure 2 is an end elevation, showing an enlarged view of the arrangement of the outer end of the shipper-rod.

Figure 3 is a vertical section of the same.

Figure 4 is a plan showing how the striker I, fig. 1, is attached to the mule-carriage.

B C, fig. 1, represents the end of a mule-frame, made in the usual manner. I construct a shipper, E F, fig. 1, which swings on a pivot at E, and is controlled by the guide H, so that it can vibrate in one plane only. Its upper end is provided with a loop or fork, F, through which the driving-belt passes. Attached to the shipper, at L, is the rod D E', which has an adjustable link, N, figs. 1 and 2, attached by the means of a screw, as shown in the drawing. Attached to the frame C, figs. 1, 2, and 3, is a standard, R, on the upper end of which a swinging bar, M, is pivoted by the pin P. The swinging bar M has a screw, s, passing through the slot in the link N, so that it may swing towards the front of the machine—that is, in the direction of the arrow, fig. 2—without moving the bar D E', but if the swinging bar is moved in the opposite direction, the screw s will come in contact with the end of the link N; and thus cause it, together with the rod D E' and the shipper E F, to move. Attached to the mule-carriage A are two adjustable strikers, K and I, K being adjustable by means of the two set-nuts V V', the striker I being fastened to the mule-carriage by means of two screws, t t', figs. 1 and 4, which pass through a slot, as shown in fig. 4, and it is also adjustable.

The operation of my machine is this: As the mule runs back, the striker K comes in contact with the swinging bar M, and thus operates the shippers E F. This action takes place just before the mule arrives at the limit of its outward motion, so that it is not stopped abruptly.

By a proper adjustment of the striker K and the link N, the shipping of the belt may take place at any desired point in the backward passage of the mule-carriage. The point in the passage of the mule at which the shipping of the belt should take place depends upon the rate of speed at which the machine is running.

The striker I acts directly on the shipper E F, in the forward passage of the mule, as will be readily understood from the drawings.

What I claim as my invention, and desire to secure by Letters Patent, is—

The combination and arrangement of the swinging bar M with the link N, the rod D E', and the shipper E F, substantially as described and for the purpose set forth.
